ELECTRIC-ELEVATOR-CONTROL SYSTEM.

No. 820,499.

Specification of Letters Patent.

Patented May 15, 1906.

Application filed March 13, 1905. Renewed November 24, 1905. Serial No. 288,853.

To all whom it may concern:

Be it known that I, JOHN D. IHLDER, a citizen of the United States, and a resident of New York city, in the county of New York

5 and State of New York, have invented certain new and useful Improvements in Electric-Elevator-Control Systems, of which the following is a specification.

10 My invention relates to the control of elevators, and more particularly to the control of electric elevators, and has for one of its objects to provide means whereby the elevator-car may be brought to rest at any predetermined point in the path of its travel either by 15 the car-operator or by automatic means independent of the operator and making it possible to effect a landing or stop exactly at the desired point regardless of the load, speed, or direction of travel of the elevator-car and not 20 depending upon the skill of the operator to effect such landing.

25 My invention further consists in the construction and arrangement of circuits herein-after more fully described, and shown in the accompanying specification and drawing.

The drawing represents more or less diagrammatically an electric-elevator system embodying my invention, and in which—

30 + and — designate, respectively, the positive and negative mains of a source of current-supply.

10 represents what I shall call a "potential-switch."

20 is a magnet which controls a number of 35 contacts operating to introduce or cut out, as the case may be, the speed-controlling resistance 30 and the series field 40.

40 50 designates a magnet-switch which controls the resistance 35, the extra field 70, and 45 a circuit to the contact 8'. The small magnet 80 controls the circuit to the magnet 60. This latter magnet 60 operates to short-circuit the resistance 90, which is in series with the extra field 70.

45 100 represents the shunt-field, and 110 the hoisting-motor armature, having the brushes 111 and 112.

120 and 130 are magnets controlling various circuits leading to the brake-magnet 140 50 and the motor-armature 110.

160 is a manually-operable switch and may be advantageously placed in the elevator-car. 190 designates a safety-switch, also operated by hand.

200 and 300 are the top and bottom limit-switches, respectively, and operate to stop the elevator-car should it for any reason overrun its normal travel.

Having described very briefly each of the several parts shown on the drawing, I will 60 now go into a more detailed description of these parts and at the same time trace the various circuits.

The fine black lines represent the operating, brake, and shunt-field circuits, while the 65 heavy black lines designate the main and motor circuits, the extra field-circuit being shown by a black line of medium thickness.

The potential-switch 10 is shown held in its upward position against the tension of a 70 spring (not shown) by the magnet-coil 11 and plunger 12, this latter being fastened to the insulator 4. This switch has two arms fastened together by the insulation 4 and pivoted about the rod 5. These arms carry 75 at their upper ends contacts 1 and 2, which serve to connect the + and — mains of the source of supply with the wires 7 and 6, respectively, when the switch is in its upper position. With the switch in this position 80 the — main is connected also to the small fixed contact 3. At the lower end of this switch is a contact 8, insulated from the switch and adapted to engage the fixed contact 9 directly under it when the magnet-coil 85 11 is deenergized, thereby allowing the switch to drop to its lower or open position. The limit-switches 200 and 300 are normally closed, holding their respective contacts in 90 electrical connection either by a weight or spring and when operated by the car overrunning its travel open the circuit to the potential-switch coil 11 through the wire 14. This wire 14 is connected to the — main by 95 wire 6 when the switch is in its upper or closed position. The other terminal of the coil 11 is connected through the small resistance 13 and switch 190 to the + wire 7. The potential-switch 10 is closed by hand, after which it will be held in its upper position by the coil 11 so long as there is sufficient potential in the main line. The circuit to the magnet 11 may also be opened by the operation of the safety-switch 190, its circuit to the + line being thus broken.

100 The wire 7 is connected to the fixed contacts 15, 17, 18, and 21, directly under which contacts are movable contacts 22, 23, 24, and

105

25, respectively. The contacts 22 and 23 are mounted on the insulation 26, which is carried on the upper end of the rod 28. In a similar manner the contacts 32 and 33 are 5 mounted on the insulation 31, which is also carried by the rod 28. At the lower end of the rod 28 is fastened the plunger or solenoid-core 29, adapted to be raised by the magnet-coil or solenoid 130 whenever the latter is sufficiently energized. As the plunger is raised it will carry the rod 28 and insulating-pieces 26 and 31 upward, together with the contacts mounted thereon. The contact 22 will make contact with the contacts 15 and 16, while 15 the contact 23 will be electrically connected to the contact 17. The raising of the rod 28 will also break any connection that may exist between contacts 32 and 34 and 33 and 36, respectively. Contacts 32 and 34 and 33 20 and 36 are in contact when the plunger 29 is in its lowermost position.

In order to trace the circuit to the motor, it will be necessary to energize either the coil 130 or 120. Let it be supposed that the coil 25 130 has been energized to raise its plunger 29. By virtue of the connections established current will flow by way of the + main and wire 7 and contact 15 to the contact 22. The contact 22 is connected by wire 37 to the contact 38, since the switch of coil 120 is in its lowermost position when the switch of coil 130 is in its uppermost position. Therefore contact 38 is at this time in contact with the contact 39. These two magnet-switches 30 controlled by the magnets 130 and 120, respectively, have a mechanical connection between them which is not shown on the drawing, but is most fully described in a former patent issued to me on July 8, 1902, 35 No. 704,336. It will therefore be sufficient to state in this connection that owing to a mechanical connection between said switches in the form of a rocking beam one switch-plunger, such as 29, when raised by its magnet moves the other switch controlled by the magnet 120 to its lowermost position. The switch thus moved will establish connections between the contacts mounted on the lower insulating-piece and the fixed contacts 40 directly below these movable ones, respectively. Thus when one switch is operated the other switch is always moved to its lowermost position, this mechanical connection preventing both switches from being moved 45 to either their lowermost or their uppermost position at the same time. The circuit from wire 37 is continued through wires 41 and 42 to the motor-armature brush 112. Passing through the motor-armature 110 the circuit 50 goes by brush 111 to wire 43 and through contacts 44 and 45 to the wire 46. Following this wire to the right this circuit can be traced to the speed-controlling resistances 35 and 30. The right-hand terminal of these 55 resistances is connected to one side of the se-

ries field 40 by wire 47, the other end of the series field being connected to the - main 6. It will therefore be seen that a circuit has been completed from the + main to the - main, including the motor-armature, the speed-controlling resistance, and the series fields. The shunt-field 100 has one side connected by wire 37 and contact 22 to the other main 7 and the other side directly to the negative or - main 6. When the contact 22 engaged the fixed contacts 15 and 16, a circuit was established to the magnet-coil of the brake 140 by the wire 51 and resistance 52, and as the brake-coil has its other terminal 56 connected to the small contact 3 of the potential - switch the brake-magnet, together with the resistance 52, will form a shunt-circuit across the main line, receiving current at the full-line potential. The magnet-coil 140 will be fully energized and operate to 80 raise the plunger 53, carrying the weighted brake-shoe 54 away from the friction-pulley 55, said friction-pulley being preferably mounted on the motor-shaft.

The extra field 70 has one terminal connected by wire 37, contacts 38 and 39, and wires 41 and 42 to the brush 112 of the motor-armature. The other terminal of the extra field is connected by wire 64 to the extra field resistance 90, which in turn is connected by wire 63 and flexible cable 62 to the contact-plate 59. This contact-plate is in electrical connection with the fixed contact 58, which is connected by wires 57 46 and contacts 45 and 44 and wire 43 to the armature-brush 111. It will therefore be seen that the extra field 70, having the resistance 90 in series with it, is connected across the armature-brushes and is therefore in shunt to the motor-armature.

It has been shown that when the coil 130 is energized to raise its plunger 29 certain connections will thereby be established which will cause the brake to be released and the hoisting-motor to be set in motion. Now 110 in order to show how the coil 130 was energized it will be necessary to describe the operation of the manually-operated switch 160 and the floor-controller 150. The floor-controller 150 comprises a number of conducting-strips—such as 119, 121, 128, 124, 87, &c.—preferably made of copper and rigidly fastened to a base of some insulating material. Slate might be used to advantage for this purpose. The conducting-strips, together with the insulating-base, are arranged so as to be revolved about a central fixed axis by some moving part of the elevator-machine. One way to accomplish this would be to connect a large sprocket-wheel on the 115 floor-controller by means of a chain to a small sprocket-wheel keyed to the drum-shaft, so that the floor-controller would have a relatively slow motion. Adjacent to the path of travel of the several conducting- 120 strips are a number of contacts, such as 125 130

strips are placed fixed insulated contacts or brushes, such as 122, 101, 103, 88, 127, &c. These are adapted to engage or disengage the strips whenever the latter are revolved 5 so as to make or break contact with them.

The manually-operable switch 160, which, as before stated, may be located in the car or in the near vicinity, comprises a pivoted lever 65, which is adapted to pass over and 10 make contact with the metallic contact-strips 66 67 68 69 71 73, &c., these latter being rigidly fastened to some insulating-base, such as slate. The contact-strips 68 and 73 are electrically connected together, and by 15 the wire 76, switch 190, and wire 72 are connected to the positive main 7. These two strips therefore constitute the positive feed to the switch 160. In moving the lever 65 to the left it will engage the contact-strip 66. 20 This operation merely connects the lever 65 with the wire 74 and produces no further results. On further moving the lever to the left it will engage also the contacts 67 and 68. This operation will result in connecting together 25 the wires 74, 75, and 76—that is, the wires 74 and 75 have been connected to the positive main. 74 is connected to the brush-contacts 77, 78, 79, and 84, these four brushes being in contact with the contact-strip 85 in 30 the position of the floor-controller, as shown on the drawing. For the time being there will be no further circuit through the wire 74. By way of wire 75 and contact-brush 35 connection is made to contact-strip 87. Contact is made between brushes 86, 88, and 125 by means of the contact-strip 87 and the intervening brushes and their connections. The wire 89 connects the contact 88 and one terminal of the magnet-coil 130, the other 40 terminal of this coil being connected by wire 91 to the main. A circuit is therefore established through the coil 130 when the arm 45 is moved into contact with the strip 67. The said coil 130 will raise its plunger 29, which, as before pointed out, will operate to 50 start the motor and hoisting machinery to raise the car. The motor will run at slow speed, however, since its armature receives current at a potential considerably lower 55 than the supply-mains, owing to the resistances 30 and 35 being in series with the armature of said motor, and since the three field-windings are excited they will produce a much more powerful magnetic field than is required to run the motor at its normal speed, thus further tending to keep the motor at a low rotative speed. The accelerating-magnet 20 controls the operation of the 60 five contacts 92, 93, 94, 95, and 96, which are pivotally mounted and when energized by the magnet-coil 20' are brought into contact, respectively, with the contacts shown directly above the movable contacts. These movable contacts may be placed at different 65 distances from the magnet 20 in order that

they shall operate consecutively in some pre-arranged order. One terminal of the magnet-coil 20' is connected to the wire 37, which wire is connected, as before pointed out, to the armature-brush 112 when the magnet 70 130 is energized. The other terminal of the magnet-coil 20' is connected through the contacts 97 and 98 to a point 99 on the speed-controlling resistance 30. From here by way of the resistance 35 and wire 46, contacts 75 44 and 45, and wire 43 there is a connection to the armature-brush 111. Therefore the magnet-coil 20' forms a shunt to a circuit comprising the motor-armature, resistance 35, and a very small portion of the resistance 80 30. When current is first put onto the motor, the same being at rest, the voltage across the terminals of the magnet-coil 20' will be low, owing to the manner in which it is connected. As the motor, however, accelerates 85 in speed this potential will gradually rise, and the contacts 92, 93, and 94 will operate in their numerical order to cut out or short-circuit the resistance 30. The contact 95 in this manner cuts out a portion of the series 90 field 40, and the contact 96 cuts out or short-circuits the remainder of the series field. The motor will now run at a somewhat higher speed, having had the greater portion of the resistance in series with it cut 95 out and having had its series field short-circuited.

The speed-magnet 50 is energized when the operator moves the lever 65 to its extreme position—that is, when the said lever 100 65 connects the contact-strips 68, 69, and 71. Current will then flow from the positive wire 76 to contact 71, contact-brush 101, and the contact-strip 102 will become alive. Bearing against this contact-strip 102 is the brush 103, which by wire 104 is connected to one terminal of the coil of magnet 50. The other terminal of this magnet is connected by the wire 106 to the negative main 6. The coil of magnet 50 will by reason of being connected across the positive and negative mains, through the operating-switch 160 and floor-controller 150, become energized and will raise its plunger 105, carrying on its upper end the contact-plates 107 and 59. These 115 contact-plates are rigidly mounted upon an extension of the magnet-plunger 105, but insulated from it. They are adapted to make or break contact with the fixed contacts 108, 109, 58, and 61. These fixed contacts are adjacent to the path of travel of the plates 107 and 59.

62 designates a flexible cable which is connected to the contact-plate 59 and wire 63.

As soon as the magnet-switch 50 has been 125 energized the contact-plate 107 will establish a connection between the fixed contacts 108 and 109, which will short-circuit or cut out the resistance 35 and at the same time open the connection between the fixed con- 130

tacts 58 and 61 and also break the connection between the contact 58 and the wire 63. This last-named operation will open the circuit supplying the extra field 70 through the 5 resistance 90. The motor will now run at its normal full speed, having all of the resistance in series and the armature resistance, together with the series field, short-circuited and having the extra field circuit broken at 10 the contact 58, the motor-field being now excited by the shunt-field 100 only.

As the car approaches a landing at which it is desired to stop the operator will bring the switch-lever 65 back until it breaks connection 15 with the contact-strip 71. This will at once deenergize the coil of magnet-switch 50, allowing the plunger 105 to drop and cause the contact-plate 107 to disconnect the fixed contacts 108 and 109 and by so doing to insert 20 the resistance 35 in the armature-circuit. At the same time a circuit will be made through the resistance 90 and extra field 70, which will cause the motor to slowdown to a considerable extent by reason of 25 the increase of field magnetization and the shunting of current from the armature through this circuit. By bringing the switch-lever 65 to the center or off position the circuit to the coil 130 will be broken, the plunger 30 29 will drop, and thus the supply-current will be shut off from the motor. The extra field, having the resistance 90 in series with it, being connected as a short shunt across the armature-brushes, will be energized by the 35 current generated by the revolving armature, which will thus produce a powerful dynamic brake, which action, in conjunction with the friction-brake controlled by magnet 140, will quickly bring the motor and hoisting 40 machinery to rest.

Thus far little has been said about the operation of the floor-controller 150; but a more detailed description will now be given.

As illustrated in the drawing, the floor-controller 45 is designed for six floors or landings. This number, however, may be more or less. As previously described, the floor-controller contact-strips, together with their insulated base, are slowly revolved one way or the other, 50 depending upon whether the elevator-car is ascending or descending. In order to describe the operation of this floor-controller, it will be assumed that the elevator-car is somewhere between the third and fourth floors. 55 The floor-controller, as shown, corresponds with such a position of the elevator-car. It will further be assumed that the elevator-car is traveling upward at full speed, the lever 65 being in the extreme left-hand position 60 and the floor-controller being slowly revolved in a counter-clockwise direction. Suppose the operator in the car wished to have the car stop automatically at the fourth floor. To do this, he merely brings the operating-lever back toward the center until it engages the

three contact-strips 67, 66, and 68. As soon as the lever 65 passes off the contact-strip 71 it causes the magnet-coil of 50 to drop its plunger, and thus, as has been previously pointed out, insert the resistance 35 into the 70 armature-circuit and at the same time energize the extra field 70. This will reduce the speed of the elevator-car, and about this time the floor-controller has revolved into such a position that the contact-brush 79 has been 75 brought into engagement with the small contact-strip 110'. The strip 110' is connected to the circular strip 111', which engages at all times the contact-brush 127. The brush 127 is connected by the wire 113 to one terminal 80 of the magnet 80, its other terminal being connected to the negative main 6. A circuit through the coil of magnet 80 is therefore established and the contact 82 will be drawn against the action of the spring 83 into contact with the fixed contact 81. This will place the magnet 60 across or in shunt to the motor-armature, causing the magnet 60 to be energized and to operate its contacts in a well-known way to short-circuit the resistance 90 in consecutive steps. The amount of resistance 90 being thus cut out or short-circuited depends on the extent of magnetization which has been produced by the coil of magnet 60, and this in turn depends upon the 95 potential across the armature-brushes, which will be proportional to the motor speed and load carried by the elevator-car. The contact 114 differs from the other contacts of the magnet 60 in that it has secured to it but insulated from it a small contact 97. This contact 97 is normally in contact with the fixed contact 98, and these two contacts complete the circuit when in such position to the accelerating-magnet 20. When, however, the 100 contact 114 is carried upward by the magnet 60, it carries the contact 97 out of engagement with the contact 98, which will break the circuit to the magnet 20, and thereby deenergize it, thus cutting into circuit the resistance 30 and series field 40. By inserting the resistance 30 in this manner in series with the armature the current in the extra field may be kept to a much lower amount than would be possible were the series resistance 105 30 not included in the armature-circuit and acting in conjunction with the extra field 70. The current flowing through the extra field 70 will depend upon the action of resistance 90, which is in series with it, and the load in the 110 car will automatically regulate the resistance and resultant current, so that a predetermined slow-down speed for different loads is attained. This is fully explained in my Patent No. 710,581, granted October 7, 1902, for elevator. By this time the car has ascended until within a short distance of the desired landing or floor, and the next operation of the floor-controller will be when the brush 116 engages the small insulated contact-strip 117. 115 120 125 130

This strip not being electrically connected to anything, the result will be to break the connection between the contact-strip 121 and the wire 75. Now this wire 75 is the positive feed for the wire 89, which is one terminal of the magnet-coil 130, being connected by brush 88 to the contact-strip 121, which has first been rendered dead. The brush 122, which also is in contact with the strip 121, 5 being connected to the contact 69 of the operating-switch, is open-circuited at that contact. Therefore the brush 122 cannot furnish current to the contact-strip 121, and since the contact-brush 88 can only be supplied with current from the brush 86 when the various parts are in the position which has been assumed the circuit to the magnet-coil 130 will be opened and its plunger will drop, cutting off the supply of current to the motor, 15 the motor-circuit being broken at the contacts of the switch connected to said plunger. The circuit of the brake-magnet is at the same time broken, causing the friction-brake to be applied. If the operator should at any 20 point of the car travel leave the switch-lever in either of its extreme positions, so that the contacts 71, 69, and 68 are connected, the car will continue to ascend or descend until stopped automatically either at the top or 25 bottom floor by the action of the floor-controller. If the switch be brought to such position that the contact-strips 68 and 69 are engaged by the lever 65, the car will ascend or descend at slow speed until the floor-controller switches automatically effect the slow-down and stop at the top or bottom floor. 30 In other words, the car will stop automatically at the desired limits of its travel through the action of the floor-controller, whether the car has been traveling at fast speed or slow speed, unless the operator's lever has been moved to the automatic position or to the center or off position to stop the car at some intermediate point.

45 Let it be supposed that the car is running up at full speed, the lever 65 being left in its extreme left-hand position. The first step of the automatic stop will then be when the car is some distance away from the landing. 50 The contact-strip 102 will then run off of the contact-brush 101. This will deenergize the contact-strip 102, and consequently the brush 103, which engages it. The brush 103 is connected to the magnet-coil 50, whose 55 circuit is broken at the controller. The switch controlled by the coil will then operate to reduce the speed of the traveling car. As the car ascends still farther, but at a reduced speed, the next operation of the floor-controller will be when the contact-block 124 passes under and engages the contact-brush 125. This will at once establish a circuit to the magnet 80 through contact-brush 127. Magnet 80 will be energized to close a circuit 60 through contacts 81 and 82 and the magnet

60, the said magnet and the parts operated thereby being the means for adjusting the speed of stopping in accordance with the load. The last step of the floor-controller occurs when the block 121 passes from under the contact-brush 122, causing the circuit to the magnet-coil 130 to be interrupted and the car to be stopped. 7c

In the event of the potential switch being thrown manually while the elevator is running, the mains 6 and 7 would be entirely disconnected from the source of current-supply. The knife-contact 8 would in this case engage the fixed contact 9, and the extra field would at once be energized through a small portion of the resistance 90. The opening of the switch 10 also opens the circuit to the brake-magnet 140 at the contact 3, and the hoisting-motor will at once come to rest. The potential switch will operate to stop the hoisting-motor in a similar manner should the circuit to its holding-magnet 11 be broken at either of the limit-switches 200 or 300, these limit-switches being so placed as to operate whenever the elevator-car over-runs or exceeds its normal travel. The same result can be accomplished by the safety-switch 190 being opened. This switch not only opens the circuit to magnet 11, but cuts off all current-supply to the operating-switch 95 160.

In the description of the various operations brought about by the manipulation of the several parts either automatically or otherwise it has been assumed for the purpose of illustration that the elevator-car has been going only in an upwardly direction. Should the operating-switch lever 65, however, be moved from its center or "off" position to the right, the various operations will 100 take place in a similar manner, except in this case the magnet-coil 120 instead of 130 will be energized. The various motor connections will be established and the armature-circuit will be made in such a way as to cause 105 it to revolve in an opposite direction to what it revolved when the car was ascending. The floor-controller will now revolve in a right-handed or clockwise direction, bringing about its several connections and arrangements of circuits in a manner already described in connection with an ascending car, the operation of the floor-controller being the same for all of the floor-landings except the extreme top or bottom landings. 115 120

The magnets 20 and 60 are shown as operating a number of movable contacts directly under them. I do not wish to be limited to any definite number of such contacts, as I may use more or less. The greater the number that are used, however, the smoother will be the act of starting and stopping. The floor-controller is also shown as being comprised of a number of contact-strips mounted on a flat insulating-base. These strips might 125 130

just as well be mounted upon the periphery of a drum and having the several brush-contacts pressed against them, or the floor-controller may consist of sets of stationary 5 switches placed in the hatchway and operated in proper sequence by cams on the car to effect the gradual and automatic stopping of the car, as hereinbefore described. In such case there would be a double series of 10 switches in each set, one series of each set being operated on the downward motion of the car and the other series of each set being operated on the upward motion of the car. Furthermore, although the floor-controller is 15 here shown for six floors, it may be constructed for any number of floors.

Other changes might be made in the system as diagrammatically represented on the drawing without departing from the spirit 20 of my invention.

Therefore, not wishing to be limited to the precise construction of details as shown and described, what I claim as new, and desire to secure by Letters Patent, is—

- 25 1. The combination with a car and its motor, of motor-controlling means, automatic means for stopping the car with varying loads at the limits of its travel and at any predetermined intermediate point, and means 30 for rendering inoperative only that part of said automatic means by which the car is stopped at any predetermined intermediate point.
- 35 2. The combination with a car and its motor, of motor-controlling means, automatic means for stopping the car with varying loads at the limits of its travel and at any predetermined intermediate point, and means 40 for rendering inoperative at will only that part of said automatic means by which the car is stopped at any predetermined intermediate point.

- 45 3. The combination of a car and its motor, of motor-controlling means, automatic means for gradually stopping the car with varying loads at the limits of its travel and at any predetermined intermediate point, and means 50 for rendering inoperative at will only that part of said automatic means by which the car is stopped at any predetermined intermediate point.

- 55 4. The combination of a car and its motor, of motor-controlling means, automatic means for stopping the car with varying loads at the limits of its travel, and at any floor-level in the traverse of said car, and means for rendering inoperative only that portion of said automatic means by which the car is stopped at any floor-level.

- 60 5. The combination of a car and its motor, of motor-controlling means, automatic means for gradually stopping the car with varying loads at the limits of its travel and at any floor-level in the traverse of said car, and means for rendering inoperative only that

portion of said automatic means by which the car is stopped at any floor-level.

6. The combination of a car and its motor, of motor-controlling means, automatic means connected to reduce the speed of said motor 70 before stopping and to vary such reduction of speed in accordance with the load so that the car will stop at the limits of its travel and at any floor-level desired, and means for rendering inoperative only that portion of said automatic means by which the car is made to stop at a desired floor-level.

7. The combination of a car and its motor, of motor-controlling means, automatic means for reducing the speed of said motor as the 80 car reaches either limit of its travel and also as it reaches any desired floor-level and to vary such change of speed in proportion to the duty, and means for rendering inoperative at will only that portion of said automatic means by which the car is stopped at a floor-level.

8. The combination of a car and its motor, of motor-controlling means, automatic means for gradually stopping said car at the limits 90 of its travel and at the same predetermined intermediate point regardless of the load, direction of travel or speed, and means for rendering inoperative at will that portion of said automatic means by which said car is stopped 95 at the intermediate point.

9. The combination of a car and its motor, of motor-controlling means, automatic means for gradually stopping said car at the limits of its travel and at the same predetermined 100 intermediate point regardless of the load, direction of travel or speed, and manually-operable means for rendering inoperative at will that portion of said automatic means by which said car is stopped at the intermediate 105 point.

10. The combination of a car and an electric motor for operating same, with electric circuits and connections for gradually and automatically stopping said car with varying 110 loads at the limits of its travel and at any intermediate point, means for changing the relation of said circuits and connections at will so that said car will stop automatically only at the limits of its travel.

11. The combination with a car and its motor, of means for controlling the starting, stopping or reversing of said motor, motor-controlling means connected to reduce the speed of the motor at the limits of its travel 120 and at predetermined intermediate points and to vary such reduction of speed inversely to the load, and means for preventing the stopping of the car at any of said intermediate points.

12. The combination with a car and its motor, of means for controlling the starting, stopping or reversing of said motor, motor-controlling means connected to automatically reduce the speed of the motor at the lim- 125 130

its of its travel and at predetermined intermediate points and to vary such reduction of speed inversely to the load, and means for preventing the stopping of the car at any of said intermediate points.

13. The combination of an elevator-car and a motor for operating same, with motor-controlling means, automatic means for gradually stopping said car with varying loads at any floor-level, and means comprising a switch for rendering said automatic means inoperative except at the limits of travel of said car.

14. The combination of a car and its motor, with motor-controlling means, automatic means for gradually stopping said car with varying loads at the limits of its travel and at same intermediate points, electric circuits and connections comprising an electric switch for rendering said automatic means inoperative at will except at the limits of travel of said car.

15. The combination of a car and its motor, with motor-controlling means, automatic means for gradually stopping said car with varying loads at the limits of its travel and at same intermediate points, electric circuits and connections comprising a manually-operable electric switch for rendering said automatic means inoperative at will except at the limits of travel of said car.

16. The combination with a car and its motor, of motor-controlling means, means comprising a floor-controller, a single switch connected thereto, and electric circuits and connections to gradually and automatically stop said car at the limits of its travel, and at a plurality of floor-levels by the operation of said switch while the car is in motion and at a sufficient time before said car reaches a desired floor-level.

17. The combination with a car and its motor, of motor-controlling means, means comprising a floor-controller, a plurality of contacts thereon for a plurality of floors, a switch comprising a plurality of contacts and an arm adapted to engage therewith, and electric circuits and connections, to gradually and automatically stop said car with varying loads when the said switch is in one position and to operate said car to the limit of its travel when said switch is in another position.

18. The combination with a car and its motor, of motor-controlling means, means comprising a switch and floor-controller for gradually and automatically stopping said car with varying loads substantially at the level of any floor when said switch is in one position and to operate the car at a slow speed and to thus stop the car only at the limits of its travel when said switch is in another position.

19. The combination of a car and its motor, with motor-controlling means, means comprising a switch and floor-controller for gradually and automatically stopping said car with varying loads at any desired floor-level when the switch is in one position and to operate said car at a maximum speed and to thus gradually and automatically stop the car only at the limits of its travel when the switch is in another position.

20. The combination with an elevator-car and its motor, of motor-controlling means, means, comprising a floor-controller and a switch having a plurality of operative positions, for gradually and automatically stopping the said car with varying loads at any floor-level after the switch is moved to one position, to operate the car slowly and thus stop the same only at the limits of its travel when said switch is moved to another position, and to operate said car at a maximum speed and thus stop the same only at the limits of its travel.

21. The combination with a car and its motor, of motor-controlling means, means comprising a switch for operating said car at a maximum speed and gradually and automatically stopping said car with varying loads at the limits of its travel when the switch is in one position and for thus stopping a car with varying loads at a same predetermined position.

22. In a motor-controlling apparatus, the combination with a motor, of an extra field and variable resistance in shunt with the armature-terminals, a load-magnet to co-operate with said variable resistance, an extra resistance in series with the armature and means for simultaneously short-circuiting said resistance, break the extra field-circuit, and prevent the said load-magnet from being energized.

23. In a motor-controlling apparatus, the combination with a motor, of an extra field and variable resistance in shunt to the armature-terminals, a load-magnet for short-circuiting said variable resistance, and means for simultaneously breaking the circuit of the extra field and variable resistance and a circuit leading to said load-magnet.

24. The combination with a car and its motor, of motor-controlling means, automatic means for gradually stopping the car with varying loads at the limits of its travel, circuits and connections and means for changing the relation thereof when desired for automatically and gradually stopping the car with varying loads substantially level with any intermediate floor.

25. The combination with a car and its motor, of motor-controlling means connected to automatically reduce the speed of the car with varying loads before stopping substantially level with the top or bottom floors, circuits and connections and means for changing the relation thereof to automatically re-

duce the speed of the car and stopping the same substantially level with any intermediate floor.

26. The combination with a car and its motor, of motor-controlling means, means connected thereto for automatically changing the speed of the motor as the car reaches the top or bottom floor and to vary such change of speed in proportion to the load so that the car shall stop substantially at the floor-level, circuits and connections and means for changing the relation thereof so that the speed of the motor shall be automatically reduced and the car stopped at any desired intermediate floor.

27. The combination with a car and its motor, of motor-controlling means connected to automatically change the speed of the motor as the car reaches the top or bottom floor and to vary such change of speed in proportion to the load until the car stops substantially level with the floor, circuits and connections comprising an electric switch so constructed and arranged that the speed of the car shall be automatically reduced and stopped level with

any intermediate floor dependent upon the position of said switch.

28. The combination with a car and its motor, of motor-controlling means connected to automatically change the speed of the car as the car reaches the top or bottom floor and to vary such change of speed in proportion to the load so that the car shall stop substantially level with the floor, a floor-controller connected to automatically control said motor-controlling means, and electric circuits and connections including an electric switch connected to said floor-controller so constructed and arranged that said floor-controller shall automatically control said motor-controlling means to thus stop the car substantially level with any intermediate floor when the switch is moved to automatic position.

In witness whereof I hereunto affix my signature.

JOHN D. IHLDER.
